UNITED STATES PATENT OFFICE.

HERMANN MEHNER, OF BERLIN-CHARLOTTENBURG, GERMANY.

METHOD OF CALCINING ALKALINE-EARTH CARBONATES.

Original application filed February 14, 1922, Serial No. 536,569. Divided and this application filed April 10, 1925. Serial No. 22,210.

To all whom it may concern:

Be it known that I, HERMANN MEHNER, a citizen of the German Republic, residing at Berlin-Charlottenburg, Germany, have 5 invented certain new and useful Improvements in Methods of Calcining Alkaline-Earth Carbonates, of which the following is a specification.

This invention is a division of application 10 bearing Serial No. 536,569, filed February 14th, 1922, and relates to a method or process of calcining alkaline earth carbonates in a furnace-generator wherein a source of heat produced above a charge maintained on a pervious grate is caused to radiate its heating energy upon the material to be treated, a gaseous intermediate layer separating the flames and the products of combustion, the volatile reaction products being led away 20 through the pervious grate and afterwards away from the generator.

My improved process is particularly applicable to the production of calcium carbonate by calcination of alkaline earth carbonates in a furnace-generator by feeding heating gases over a charge therein and in causing combustion of the gases by the admission of air into the upper portion of the furnace-generator through a pervious 30 arch thereof, and also through a filling of heat retaining material, and in providing means whereby the products of combustion may be withdrawn from the furnace-generator continuously through its top, and 35 when free from carbon or the like the heat will be radiated upon a charge on the pervious grate and the gaseous products of calcination of the material on the grate will be drawn out of a space in the furnace-generator below said pervious grate.

In carrying out my process, the relatively cool gases used for calcining the material are admitted above the charge and form an intermediate protecting layer between the 45 charge and the burning gases whereby the flames caused by the combustion of the gases will be remote from the charge, the main consumption taking place immediately below the arch or upper portion of the furnace-generator and being radiated upon the charge maintained upon the pervious grate.

When employing my process for burning limestone or calcining alkaline earth carbonates according to my invention, the combustible gases are admitted directly above

the charge of limestone, combustion is effected in the upper part of the furnace along with heated air. Steam or water vapor is fed into the furnace-generator simultaneously with the fuel gas, and the calcination 60 of charge of limestone results in the production of carbon dioxide, or other resulting volatile products, the product being discharged through the pervious grate upon which it is supported.

In carrying out my process the intermediate layer of gas and steam, to a great extent, protects the charge from direct contact with the burning gaseous fuel and the initial flames produced are kept away from 70 the charge, the generated heat being radiated from the combustion zone upon the charge through this protecting gaseous layer. The heat passes down through the charge and out of the furnace-generator with the products of calcination. A great saving of heat is effected by passing air into the upper zone 75 of the furnace-generator and then radiating the heat from the upper zone of the furnace-generator through the intermediate zone and upon the charge maintained on the pervious grate, which charge contains lime and carboniferous material.

In the accompanying drawing which illustrates my invention, 85

Figure 1 is a cross section of a furnace-generator constructed to accord with my invention; and

Figure 2 is a longitudinal section.

The furnace-generator is provided with an 90 arch 1 of pervious material which may be unglazed fire brick or the like, and below the arch are the usual walls which carry a grate of pervious material upon which the charge is placed, and below said grate is a 95 space having an outlet 6 with a damper or controlling means 7. The arch of the furnace-generator is provided with an opening 4 leading into a chimney and provided with a damper or controlling means of usual 100 construction.

The furnace-generator is also provided with hoppers 8 which communicate with passages through the arch, the charge being fed upon the grate 2 through said hoppers. 105 The arch 1 is provided with a filling 22 of suitable heat retaining pervious material, for instance, broken stone, and said filling is separated from the vertical walls of the furnace by angle irons or plates 5. The entire 110

furnace-generator is encased by a sheet metal covering 24, said covering or casing having an opening 25, through which air is admitted to the filling 22 and is passed therefrom through the pervious arch 1 and into the upper zone of the furnace-generator, in which zone the combustion of the flame gases is consumed along with the heated air which is passed into the aforesaid upper zone of the furnace-generator.

Below what may be considered the upper combustion zone of the furnace-generator there are openings 3 and 3', through which relatively cool combustible gases and steam may be admitted into the furnace-generator above the charge placed upon the pervious grate. The products of reaction are passed downwardly through the pervious grate into a space below said grate, from whence they are discharged or drawn out of the furnace-generator by way of valved openings 6 having valves or dampers 7.

When applying the furnace-generator herein shown for burning limestone or carrying out other calcinations, the furnace-generator is charged with limestone placed upon the grate, and into this charge, steam or water vapor is fed in an appropriate manner, as through the openings 3 and 3'. The resulting carbon dioxide, or other products which are dissociated from the material placed upon the grate are discharged downward into the space below the under side of the grate and are withdrawn by suction through the openings 6.

By the manner of utilizing the heat generated within the furnace from limestone may be produced pure lime, carbon dioxide for industrial purposes which will be free from nitrogen, and a lime which is free from bitumen. The carbon dioxide may be used for the aeration of beverages and for other industrial purposes.

The simultaneous use of water vapor or steam, heated air and a gaseous fuel to produce combustion in the treatment of material from which lime may be produced by burning, and by the action of fluid liquid upon the lime, produces carbon dioxide and water vapor, which together have atmos-

pheric pressure, and consequently to discharge them from the furnace-generator the pressure therein will have to be in excess of the atmosphere, or the exhaust will have to be supplied with exhaust means. 55

I claim:—

1. The process of calcining alkaline earth carbonates in a furnace-generator to produce lime which consists in supporting a charge of an alkaline earth carbonate upon a pervious grate maintained within the lower portion of the furnace-generator, admitting relatively cool combustible gas and steam to a zone immediately above said charge, admitting air into an upper zone of the furnace-generator, said zone constituting a combustion zone wherein the combustible gas is burned and is separated from the charge by the relatively cool combustible gas and steam which form an intermediate 70 layer, radiating the heat from the combustion zone through said intermediate layer above the charge, and drawing off the products dissociated from the charge from a zone below the grate. 75

2. The process of calcining calcium carbonate in a furnace-generator to produce lime and carbon dioxide which consists in supporting a charge of calcium carbonate upon a pervious grate maintained within the lower portion of the furnace-generator, admitting relatively cool combustible gas and steam to a zone immediately above said charge of calcium carbonate, admitting air into an upper zone of the furnace-generator, said upper zone constituting a combustion zone wherein the combustible gas is burned and is separated from the charge by the admitted relatively cool combustible gas and the steam, forming an intermediate layer, radiating the heat of said combustion zone through said steam and combustible gas zone upon the charge of calcium carbonate, in order to calcine the same, and then separating the lime and carbon dioxide by withdrawing the carbon dioxide from the space below the grate. 90

In testimony whereof I affix my signature this 16th day of March, 1925.

HERMANN MEHNER.
